United States Patent Office

Des. 215,412
Patented Sept. 30, 1969

215,412

JAR OR THE LIKE

Walter J. Landor, San Francisco, Calif., assignor to Hills Bros. Coffee, Inc., San Francisco, Calif.

Filed Sept. 20, 1968, Ser. No. 13,631

Term of patent 14 years

Int. Cl. D9—01

U.S. Cl. D9—119

FIG. 1

FIG. 2

FIG. 3

FIG. 1 is an elevational view of a jar or the like embodying my new design, the side opposite that shown being the same in appearance as the side shown;

FIG. 2 is a top plan view thereof; and

FIG. 3 is a bottom plan view thereof.

I claim:

The ornamental design for a jar or the like, as shown and described.
